INVENTOR:

UNITED STATES PATENT OFFICE.

JONAS H. WIEST, OF INDIANAPOLIS, INDIANA, ASSIGNOR OF ONE-HALF TO LEONIDAS R. O'HAVER, OF INDIANAPOLIS, INDIANA.

POST-MOLD.

No. 879,078.

Specification of Letters Patent.

Patented Feb. 11, 1908.

Application filed January 31, 1907. Serial No. 364,961.

To all whom it may concern:

Be it known that I, JONAS H. WIEST, a citizen of the United States, residing at Indianapolis, in the county of Marion and State 5 of Indiana, have invented certain new and useful Improvements in Post-Molds; and I do declare the following to be a full, clear, and exact description of the invention, reference being had to the accompanying drawings, and to the letters and figures of reference marked thereon, which form a part of this specification.

This invention relates to sectional forms for use in molding plastic material such as 15 concrete into forms of fence posts or other similar posts, the invention having reference particularly to forms whereby two opposite sides of the posts are shaped.

The object of the invention is to provide 20 an improved metallic mold of the above-mentioned character adapted to be adjusted so as to form different sizes of posts, and to provide a mold that may be easily handled and be strong, durable and economical in use.

25 With the above-mentioned and minor objects in view the invention consists in an adjustable mold having two opposite side forms connected together by an elastic head form and a foot form hinged to one of the 30 side forms to be connected detachably to the other one of the side forms, the foot form being preferably extensible and the side forms being preferably extensible laterally so that posts of different thicknesses may be 35 molded thereby.

The invention consists further in the novel parts and in the combinations and arrangements of parts embodied in the construction as hereinafter particularly described and 40 pointed out in the appended claims.

Referring to the drawings Figure 1 is a 45 perspective view of the improved mold with the side forms contracted; Fig. 2, a top plan of the mold with the foot form disconnected from one of the side forms and the free ends of the side forms drawn together by the elastic head form, showing the normal positions of the side forms relatively when the mold is not adjusted for use; Fig. 3, a perspective view of the head brace of the mold; Fig. 4, a perspective view of the foot brace of the mold; and, Fig. 5, a transverse sec-

tional view taken near the foot of the mold looking towards the head end thereof.

Similar reference characters in the different figures of the drawings designate like elements or features of construction.

In a practical embodiment of the invention the main part of the mold comprises two sheet metal plates A and A' which are 60 designed to stand up edgewise when in use on a pallet or a smooth floor, the lower edges of the plates having L-section angle irons B riveted to the outer sides thereof extending from the foot ends of the plates to and 65 slightly beyond the head ends thereof, the upper edges of the side plates having L-section angle irons B' secured thereto and likewise extending beyond the head ends of the plates. The lower edges of the plates A 70 and A' are preferably turned away from the angle irons B so as to form angular lips a whereby beveled corners may be formed on the posts. A curved head form C is composed of spring steel and has its ends abut- 75 ting the head ends of the plates A and A', and is secured by bolts b to the projecting ends of the angle irons B and B'. The foot end of the plate A has a hinge part D formed thereon. A foot form E has a hinge part F 80 formed thereon which is connected by a hinge pin c to the hinge part D. An extension plate G has slots d and is connected to the foot form E adjustably by means of bolts e extending through the slots. A hasp 85 H is connected by a hinge f to a hasp plate g which is secured to the extension plate G, the hasp being provided with a hook I whereby to detachably connect the hasp with a staple J with which the side plate A' is 90 provided. The head form C and the foot form may be of any suitable height, but preferably are of the same height as the side plates A and A', if the mold is intended to form all posts of uniform thickness in one 95 direction, but when the side forms are made extensible as shown then the head form and the foot form will each extend higher than the main parts of the side forms above-described, and extension plates K and K' 100 are provided that are adjustable with respect to the plates A and A', the extension plates K and K' being provided at their upper edges exteriorly with L-section angle irons L and

L' to which are attached guide bars as M and M' for holding the extensible form plates K and K' in their proper positions with respect to the form plates A and A'. The angle bars 5 B' have finger holes h and i in their ends for convenience in lifting the mold. The guide bars M and M' have pin holes j therein, the angle bars B' having slots k therein to receive the guide bars M and M', and pins l are provided to be inserted in the holes j, either upon the tops of the angle bars B' or through 10 guide bars N, N' that are secured to the angle bars B and B'. In this construction the side form extensions K and K' may be elevated to various heights up to the heights 15 of the head and foot pieces so that various thicknesses of posts may be made. Guide strips m are secured to the side plates A and A' and extend from the angle bar B to the angle bar B' behind the guide bars N and N' so that the guide bars M and M' may be guided accurately.

An adjustable semi-circular brace is provided at the head of the mold to stiffen the 25 head form C and comprises a segment O and a segment O' that has a slot n receiving a set screw p that connects the two segments together. A foot brace is also provided for bracing the extensible parts of the side forms 30 and comprises a section P and a section P', one being provided with a set screw q extending through a slot r to adjustably hold the two sections together. The braces are both provided with hooks s at their ends that are 35 insertable in holes t in the ends of the angle bars L and L'.

In practical use the mold is to be placed on a level floor or on a pallet. The foot form may be adjusted so as to mold the posts of 40 any suitable width at the foot without materially changing the width at the head of the post, the head form C however, permitting of slight variation in the width of the head of the post, and if the head of the post is desired to have much greater or less width a 45 head form of different diameter will be substituted for the one shown herein. Having coupled the foot form so as to connect both side forms, the material is to be placed in the mold as usual and after having been tamped 50 sufficiently to permit of removal of the forms then the foot form may be disconnected by means of the hook i and may be swung away from the post, after which the foot ends of the 55 side forms may be forced apart away from the post and then lifted away entirely from the molded post which will remain to become thoroughly cured. The post of course 60 may be provided with any suitable type of binders and fencing fasteners.

Having thus described the invention, what is claimed as new is—

1. A post mold comprising a pair of side forms each consisting of a plate and angle 65 iron bars secured to edge portions of the

plate, an elastic head form attached to ends of the bars and abutting the plates of the side forms, and a foot form to coöperate with the side forms.

2. A post mold comprising two straight 70 sheet metal plates, a curved plate, four angle-bars secured to the curved plate, two of the angle-bars being secured to one of the straight plates and the other two angle-bars secured to the other straight plate, and a foot 75 form hinged to one of the straight plates and attachable to the other one of the straight plates.

3. A post mold comprising a pair of side forms having adjustable extensions for varying the height thereof, a curved elastic head form attached to the side forms, and an extensible foot form hinged to one of the side forms and attachable to the other one of the side forms. 80

4. A post mold comprising a pair of side forms each consisting of a plate and angle-iron bars secured to edge portions of the plate, one of the bars having finger-holes 90 therein at both ends thereof, a curved elastic head form attached to ends of the angle-iron bars and abutting the plates of the side forms, and a foot form hinged to one of the side forms at opposite ends of the bars and attachable to the other one of the side forms 95 at opposite ends of the bars thereof.

5. A post mold comprising a pair of side forms having extension plates connected thereto, a curved elastic head form attached to the side forms, a foot form hinged to one 100 of the side forms and attachable to the other one of the side forms, and a pair of braces attachable to the extension plates of the side forms at the head and foot forms respectively. 105

6. A post mold comprising a pair of main side form plates having angle-iron bars secured thereto and provided with slots, a pair of extensible plates having angle-iron bars secured thereto and provided with perforated 110 guide bars adjustable in the slots, pins insertable in the perforations, a curved elastic head form connecting the main side form plates together, and an extensible foot form to connect the main side form plates and also 115 the extensible plates together.

7. A post mold comprising a pair of main side forms having parallel guide bars attached thereto, extensible side forms provided with perforated guide bars adjustable 120 between the parallel guide bars, pins insertable in the perforations of the guide bars, a curved elastic head form connected detachably to the main side forms, and an extensible foot form hinged to one of the main side 125 forms and attachable to the other one of the main side forms.

8. A post mold comprising a pair of side form plates having lower angles edges, angle-iron bars secured to the plates opposite to 13

the angled edges thereof, angle-iron bars attached to the opposite edges of the plates and having finger-holes in the ends thereof, a curved elastic head form connecting the 5 plates, and a foot form hinged to one of the plates and attachable to the other one of the plates.

In testimony whereof I affix my signature in presence of two witnesses.
